PRINTING APPARATUS

Josef Róna, Budapest, Hungary

Application April 9, 1936, Serial No. 73,559
In Belgium April 8, 1935

6 Claims. (Cl. 101—35)

This invention relates to a printing apparatus, more particularly to an apparatus for the printing of box-shaped articles such as match-boxes and the like.

One of the objects of the invention is to provide an apparatus for printing advertisements or the like on boxes and more particularly on the friction surfaces or other flat sides of match-containers in a continuous manner.

Another object of this invention is to provide a printing apparatus for the above named purposes which works in a reliable manner and in which the boxes are guided by means of relatively simple construction.

Other objects of the invention will appear from the following description and the accompanying drawings which illustrate constructional forms of the printing apparatus according to the invention by way of example. In these drawings:

Figure 1 is a side view of the first constructional form,

Figure 2 is a sectional view on the line 2—2 of Figure 1,

Figure 3 is a horizontal sectional view on the line 3—3 of Figure 1 and

Figure 4 is a horizontal sectional view on the line 4—4 of Figure 2.

Figure 5 is a side view of the second constructional form.

Figure 6 is a plan view of Fig. 5 and

Figure 7 is a partly sectional view of a detail on a larger scale of the arrangement shown in Fig. 5.

Fig. 8 is a side view of the third constructional form, the frame of the apparatus being omitted,

Fig. 9 shows on a larger scale a detail of the conveyor belts,

Figs. 10, 11 and 12 show details of the apparatus according to Fig. 8 on a larger scale, Figs. 11 and 12 being sectional views on lines 11—11 and 12—12 respectively of Fig. 8.

Fig. 13 shows on a larger scale the upper part of the guiding device for the printed boxes together with a signal apparatus,

Fig. 14 is a plan view of the same.

Fig. 15 is a fragmentary view showing the end of the conveyor belt 131 opposite that appearing in Fig. 8.

In Figures 1—4 of the drawings 1 is a guide channel or guide rail on which the boxes 2 are conveyed continuously forward in an upright position by means of a suitable device. 3 is a vertical wall of the machine frame 4. In this wall a shaft 5 is supported by main bearings, driven from the power transmitting device 6 by way of the

shaft 7 and of the intermediate gearing 8, 9. The free end of the shaft 5 carries a disc 10 by which a conveyor belt 12 guided on rollers 11 is moved. By the side of the disc 10 the shaft 5 carries a cam disc 13 which, however, also forms a single piece with the disc 10. On the wall 3, a lever 15—17 is rotatably mounted at 14, the lever end 15, having a roll 16 co-operating with the cam 13. The end 17 of the lever is pivotally connected at 18 with a link 19 pivotally connected at 20 with the segment 22 rotatable in the bracket 21.

The free end of the conveyor belt 23 is mounted on the segment 22 and moves on guiding rollers 24, whereas the free end of the conveyor belt is subjected to the force of the spring 25, which is connected at its other end at 26 with a fixed part of the machine, for instance, with the rails 1.

Opposite to the section 12' of the conveyor belt 12 a second conveyor belt 27 moves, guided on rollers 28. The part of the latter belt, being over the highest guiding roller of the conveyor belt 12, is influenced by a press roller 29 mounted in a swivel arm 29' and pressed by means of the spring 29'' against the channel or rail 30 conveying the ready printed boxes. The channel 30 is joined horizontally to the said highest guiding roller 11 of the conveyor belt 12. The ready printed boxes 2 are conveyed by two belts 31, 32 the horizontal portions of which are situated above and below the boxes.

The driving of the conveyor belts 12, 27, 31, and 32 is derived in a suitable manner from the main driving gear of the machine. In the constructional form according to Figures 1—4 a belt 35 gearing 38, 39, 40 is provided for this purpose. On the shaft 41 of the pulley 40 one of the guiding rollers 42 for the conveyor belt 31 is mounted. Also on the same shaft a toothed wheel 43 gearing with the toothed wheel 44 is provided. The shaft 45 of the latter carries one of the guiding rollers 46 for the upper conveyor belt 32.

The printing of the boxes is accomplished by the printing rollers 33, 34 the boxes being carried between them by means of the conveyor belts 12, 27. The drive of these rollers is accomplished in a known manner by means of chain gears or the like. Each printing roller is at the same time the abutment of the other printing roller. The printing surfaces advantageously consist of hard rubber 50 printing blocks with letters or figures of conical cross section. The hard rubber printing blocks rest on a base of soft rubber.

The printing rollers 33, 34 are supplied with paints by means of inking devices 35, 36 in a 55

manner known per se. The drive of these devices also, is accomplished in a manner also known per se.

The apparatus works in the following manner:

The boxes 2 are conveyed forwardly in a continuous manner in the channel 1. Known means, as for example conveying belts, may be provided for this purpose. The foremost box leaves the channel at its front edge and is caught by a stop 37 fixed on the conveyor belt 23. This stop is adapted to convey the boxes separately between the conveyor belts 12 and 27, as will be herein-after described.

During the revolution of the cam disc 13 the cams 13' engage with the roller 16 of the lever. As soon as the roller 16 runs up on the cams 13', the lever 15, 17 is swung and the segment 22 is pressed down by the link 19. In this way the end 20 of the conveyor belt 23 being connected with the segment 22 is drawn downwards and the stop 37 is moved upwards.

The belt 23 together with the stop 37 carry the box upwardly until the latter is caught between the parts of the conveyor belts 12 and 27, which are substantially parallel to each other. Simultaneously with the described movement of the conveyor belt 23 the spring 25 is stretched and carries the parts back into their initial position, when the roller 16 moves into the depression between the cams 13', whereupon the stop is ready to again engage a box to be provided with printing.

During the time that the box is moved upwards between the parts 12', 27', of the conveyor belts which are substantially parallel to each other, the said box is printed. After leaving the parallel section 12', 27' of the conveyor belts the box is introduced by means of the spring pressed roller 29 into the conveying device 30, 31, 32 in the manner already described. Here the box travels further either to be subjected to further processes of treatment, or to be supplied to the packing device. Eventually in this way, the printing on the box can also be dried, this being unnecessary in the case of using quick drying printing paints.

Preferably, the printing matrices of the printing rollers 33 are interchangeable. Also, one of the printing rollers only may be provided with printing surfaces whilst the other printing roller serves merely as an abutment. The number of the printing rollers and of the matrices is dependent on the extent and number of colors of the printing matter desired.

In the second constructional form shown in Figures 5-7 the supply of the single boxes to the conveyor belts 12, 27 or to their parallel sections 12', 27', respectively, takes place in a different manner.

The drive is accomplished likewise by means of a pulley 6, carrying on its shaft 7 a wedged toothed wheel 8, driving the toothed wheel 9 on the shaft 5. On the shaft 7 is further a toothed wheel 47, which gears with the toothed wheel 48 mounted in bearings of the machine frame. The shaft of this toothed wheel carries a disc 49 (Figure 7) having an eccentric groove 50. This groove guides a roller 51, arranged rotatably in a bearing in the arm of the angular lever 52 which is mounted rotatably at 53. By means of a link 55 and pivots 54 and 56 this angular lever is pivotally connected with a bar 57 guided at 59. The bar 57 is terminated on the upper end 75 in a head 58.

Opposite to the head 58, the bottom of the guiding channel or rail 1 is provided with an opening.

The disc 49 is rotated by means of the toothed wheels 47, 48 and owing to the eccentricity of the groove 50, the roller 51 running therein swings the angular lever 52 on each revolution. By means of the link 55 the bar 57 guided at 59, is carried, its head entering the opening in the bottom of the guide 1 and moving the box 10 2 located in this opening between the conveyor belts 12, 27.

In this manner a continuous supply of the boxes 2 to the printing device is attained.

The forward motion of the boxes 2 in the channel or rail 1 is obtained in this constructional form by means of a conveyor belt 64, on which the boxes rest and by which the same are carried. The conveyor belt 64 moves on rollers 65. The shaft of one of these rollers is 20 provided with a strap-pulley 63 the drive of which is accomplished by means of a strap-pulley 61 arranged on the shaft 5.

A second strap-pulley 60 provided likewise on the shaft 5, drives the disc 40 by means of the cord 66.

In Figure 8 again 1 designates the guide channel for the boxes. In this constructional form the boxes 2 are carried, as well as in the constructional form shown in Figure 5 by means 30 of a headed bar 57, guided at 59 between the conveyor belts 75, 98 carrying the boxes through the printing device, but the drive of the bar 57 and the manner of guiding of the boxes is a different one.

On the main shaft 5 a pulley 68 is mounted being driven by a belt 67. The main shaft carries further as in the constructional form according to Figure 5 a disc 49 provided with a groove 50. The groove 50 carries a roller 51 arranged rotatably in the single armed lever 70 pivoted at 69. This lever is connected by means of the pivot 54 to the joint 55 and the latter by the pivot 56 to the rod 57. The motion of the rod is the same as in the constructional form 45 shown in Figure 5.

On the main shaft 5 further a toothed wheel 71 is arranged, gearing with a toothed wheel 73 being firmly wedged on the shaft 12. This shaft carries a disc 74, forming one of the guiding discs of the conveyor belt 75. This conveyor belt runs along one side of the large disc 77 arranged on the shaft 76 and is tensioned by a roller 78, the latter being carried by an arm 79 which is rotatably mounted on the pivot 80. The disc 78 is pressed against the conveyor belt in a suitable manner as for instance, by a spiral spring surrounding the shaft 80. This tensioning device is not shown in the drawings as such devices are well known to those skilled in the art. Also the other tensioning devices referred to in the further course of the description are pressed in the same manner.

The conveyor belt 75 runs on the opposite side of the disc 74 on guiding rollers 81, 82. Beginning at the latter roller the belt in its section 75' forms one of the substantially vertical guides for the boxes 2. In its further course the belt 75 is guided by the large disc 77, it is then continued in a substantially horizontal section 75'' and, finally, it runs round the guiding rollers 83, 84.

The toothed wheel 73 arranged on the shaft 72 gears with a further toothed wheel 85, firmly wedged on the shaft 86. The toothed wheel 85

drives the toothed wheel 88, which is carried by the shaft 87 and gears with the toothed wheel 90, wedged on the shaft 89.

This shaft 89 carries a disc 91, around which a second conveyor belt 92 extends. This conveyor belt is carried by the rollers 93, 94 and by the tensioning-roller 97 carried by the arm 96 pivoted at 95. The box 2 lifted by the rod enters between the substantially vertical section 92' of the conveyor belt 92 and the opposite section 75' of the conveyor belt 75, being likewise substantially vertical.

In the further course of the movement, that is to say, during the printing operation the boxes are carried by a third conveyor belt 98, the substantially vertical section 98' of which is opposite to the section 75' of the conveyor belt 75 and parallel to the same.

The conveyor belt is driven by a disc 100 carried by the shaft 99. This disc is driven by a toothed wheel 101, gearing with the toothed wheel 88, carried on the shaft 87. The guiding of the belt 98 is accomplished at first by the discs 102, 103. The latter disc guides the belt into the vertical section 98' and from this point the conveyor belt is taken over by the boxes 2, which latter are carried between this belt and the conveyor belt 75. By the guiding roller 104 the belt is guided over in the substantially horizontal section 98''. After the roller 104 the belt runs over the guiding roller 105, then over the tensioning roller 106 and the roller 107.

Thus the boxes individually supplied, are carried by the belts 75, 92 through the apparatus and the boxes 2 leave the same on the right hand end (in the drawings) of the horizontal parallel guide 75'', 98''. In the drawings the direction of movement of the conveyor belts is marked by arrows.

Figure 9 shows as an example a constructional form of the conveyor belt 75. In order to increase the friction of the belt on the boxes 2 for insuring movement of the latter, the conveyor belt 75 is provided on its side adjacent to the boxes with a layer of rubber or like material 75a. Of course, instead of the conveyor belt 75 the conveyor 92, 98 can be likewise constructed.

In the constructional form according to Figure 8 the printed boxes are carried over the top of a chute 108 through which the same are conveyed for further dealing or packing purposes. The supply of the boxes to the chute is effected by elastic arms 109 arranged on the boss 111 rotatably mounted on the shaft 110. On this shaft 55 is carried a pulley 112 which is driven by means of the belt 114 from the pulley 113 of the shaft 99. The rotation of the shaft 110 is controlled in such a manner that whenever a box is leaving the sections 75'', 98'' of the pit 108, one of the elastic arms 109 is in a nearly horizontal position so that the box 2 to be conveyed is pushed under this arm and enters the chute 108.

In this chute the boxes fall flatwise and enter then the guiding rail 115. This rail has an U-shaped cross section (Figures 11 and 12) and is detachably fixed on the upper end of the chute 108 by means of a clip 116 being screwed on (Figures 8 and 10). At a certain distance from the opening of the U-shaped rail 115 runs parallel an elastic metal strip 117, guiding the boxes 2 during descent in the rail. The elastic strips 117 are fastened on the rail 115 by means of clamps 118 and 118a (Figures 11 and 12). The rail 115 and the clamps 118, 118a are connected, by means of screws 119.

The clamps 118 consist in a frame, which on one side is connected with the rail 115, whereas the other part of the same is provided with a thread for a screw 120. The lower end of this screw thrusts against the elastic strip 117. By setting of the screw, the distance between the strip 117 and the rail 115 and, also, the clearance space 121 (Figure 11) for the boxes 2, can be adjusted. The boxes are adapted to pass loosely between the rail 115 and the belt 117, they must not rub on the rail 115. The screw 120 is secured in its adjusted position by the lock nuts 122, 122.

The clamp 118a (Figure 12) serves as a device for retarding the movement of the boxes passing through the lower end of the guide. With this end in view a clamp 118a is provided at the top with an opening 123 in which a bolt 124 is guided. The upper part of this bolt forms a screw 125, whereas to the lower end of the same the lower free end of the strip 117 is firmly connected, for example riveted. The bolt 124 is surrounded by a spiral spring 126, thrusting from one side on the strip 117 and from the other side on a plate 127. At this clamp the strip 117 is supported for example by means of the rivet head 128 on the upper end of the box 2, thus in failure of the space being present at the clamps 118, the spring 126 exerts on the boxes 2 entering the clamp 118a an elastic pressure which slackens the movement of the boxes. The pressure of the spring 126 can be adjusted by means of the screws 125 and the nut 129, respectively. The lock-nut 130 secures the screw 125 in the adjusted position. If the guide 115, 117 is filled with boxes up to the retarding device 118a, the boxes constitute in themselves a sufficient resistance so that after a certain period of operation of the apparatus the pressure of the spring 126 can be released and, respectively, the strip 117 can be lifted off the boxes 2.

The guiding rail 115 terminates in a horizontal part 115' returning the boxes into the upright position on a conveyor belt 131. This conveyor belt carries the boxes onto their place of destination. The end of the conveyor belt represented in Figure 8 runs over a roller 132 mounted on a shaft 133 and the shaft 133 of the roller carries a pulley 134. This pulley is driven by means of the crossed belt 137 from the pulley 136 being wedged on the shaft 135. The latter 50 carries also the guiding disc 65 for the conveyor belt 64 carrying the boxes 2 to the guide 1. The opposite end of the conveyor belt 131 extends over a roller 132a mounted on a shaft 133a as shown in Fig. 15.

The detachable connection of the chute 108 with the guide 115, 117 affords the advantage that the boxes can be conveyed further in any direction. For this purpose it is only necessary to release the clip connection 116 and to arrange the same on one of the other sides of the chute 108. In Figure 8 another conveying direction of the boxes is represented by dot and dash lines. In this case the clip 116 is arranged on the opposite side at 116' of the chute 108 and the rail 65 117 is turned 180 degrees with relation to the first described arrangement. As for the rest the apparatus remains unaltered. It is self-evident that the conveyor belt 131 will then be arranged at the proper place as indicated at 131'. It is 70 driven by a belt 137' and a pulley 134'. It is also possible to arrange the rail on the chute at an angle of 90° from the position represented by full lines, so that the boxes can be conveyed according to requirement in any direction.

In order to be able to observe the boxes and especially their correct position in the chute 108 a door 138 with a window 139 is arranged on one side of the chute (Figures 8 and 13). The door 138 is hinged at 140 and is provided with a handle 141. After turning down of the door 138 the upper end of the chute 108 becomes accessible and improperly positioned boxes as well as improperly printed boxes can be removed.

On the chute 108 is further an alarm device arranged giving a signal whenever the boxes stick in the pit or in the guide 115, 117. For this purpose a flap 143 turnable on the pivot 142 is arranged. This flap is provided with a contact piece 145 connected by the conductor 146 with one pole 147 of a source of electric current 148. The other pole 149 is connected by the conductor 150 with a contact piece 152 fixed on the pit 108 on an intermediate insulator 151. The flap 143 is normally held in closed position by means of a catch-spring 153 (Figure 14) fixed on the chute 108.

In the case of a box 2 being in the chute 108 in an irregular position which can be caused also by an irregular position of the boxes in the guide 115, 117 exerting a counter-pressure against the pile of boxes, the irregularly positioned box exerts a pressure on the flap 143 against the effect of the spring 153, the flap turns down in the position represented in Figure 13 by dotted lines and the contact 145, 152 will be closed. Thereby the circuit of the source 148 of the electric current will be closed and a visible or audible signal will be given. In the drawings an incandescent lamp 154 is represented as an example. The flashing up of this lamp indicates to the attendant that something is out of order and that the apparatus is to be stopped.

The described alarm device can also be used 40 in a manner known per se for the automatic stopping of the apparatus or to give a signal.

The constructional forms of the apparatus described as examples are adapted for printing the narrow sides of boxes, that is the usual friction surfaces of match boxes which, in this way, are provided with an effective advertisement. But the apparatus may be built within the limits of the invention so that it is adapted for printing of the broad sides of the boxes, printing on them 50 for example advertisements or marks. By means of this apparatus after the necessary constructional alterations, it is also possible, to provide box-like objects, that is, flat match packages with printing on their friction surfaces or on other places.

In the apparatus described the rail or channel 1 preferably is joined closely to the drying channel of the machine for producing match boxes, whereas the ready printed boxes are conveyed 60 from the channel or rail 30 to the device for packing the boxes. Also, the printing device is adapted to be inserted in apparatus for the production of match packages already existing, without any essential alteration of the existing parts.

What I claim is:

1. In a printing apparatus for printing box shaped articles, spaced parallel conveyor belts movable synchronously in the same direction for carrying between them the box shaped articles to be stamped, means for feeding box-shaped articles to said belts, means for driving said belts, means for guiding opposite substantially parallel portions of the belts first vertically upwardly and then in a curved path to a substantially horizon-

tal plane, printing rollers arranged opposite the edges of the belts for printing upon opposite sides of the boxes as the belts move said boxes upwardly, and means for guiding the box-shaped articles leaving the conveyor belts in a direction toward the horizontal plane occupied by said feeding means. 5

2. In a printing apparatus for printing box shaped articles, spaced parallel conveyor belts movable synchronously in the same direction for carrying between them the box shaped articles to be stamped, means for driving said belts, means for feeding said articles one by one between said conveyor belts, means for guiding opposite substantially parallel portions of the belts first vertically upwardly and then in a curved path to a substantially horizontal plane, and printing rollers arranged opposite the edges of the belts for printing upon opposite sides of the boxes as the belts move the same upwardly. 10

3. In a printing apparatus for printing box shaped articles, spaced parallel conveyor belts movable synchronously in the same direction for carrying between them the box shaped articles to be stamped, means for driving said belts, means including a reciprocating pusher for feeding said articles one by one between said conveyor belts, means for reciprocating said pusher, means for guiding opposite substantially parallel portions of the belts first vertically upwardly and then in a curved path to a substantially horizontal plane, and printing rollers arranged opposite the edges of the belts for printing upon opposite sides of the boxes as the belts move the same upwardly. 15

4. In a printing apparatus for printing box shaped articles, spaced parallel conveyor belts movable synchronously in the same direction for carrying between them the box shaped articles to be stamped, means for driving said belts, means for guiding opposite substantially parallel portions of the belts first vertically upwardly and then in a curved path to a substantially horizontal plane, printing rollers arranged opposite the edges of the belts for printing upon opposite sides of the box shaped articles as the belts move the same upwardly, and a vertical pitfall adapted to receive articles moving along said horizontal plane for stacking said articles in substantially flat condition. 20

5. In a printing apparatus for printing box shaped articles, spaced parallel conveyor belts movable synchronously in the same direction for carrying between them the box shaped articles to be stamped, means for driving said belts, means for guiding opposite substantially parallel portions of the belts first vertically upwardly and then in a curved path to a substantially horizontal plane, whereby the box shaped articles will be carried first in upright condition and then in a substantially flat condition along said horizontal plane, printing rollers arranged opposite the edges of the belts for printing upon opposite sides of said box shaped articles as the belts move the same upwardly, a vertical pitfall adapted to receive the articles moving along said horizontal plane for stacking said articles in substantially flat condition, and means for feeding said articles from the delivery end of said belts into said pitfall one by one while maintaining said articles in substantially flat condition. 25

6. In a printing apparatus for printing box shaped articles, spaced parallel conveyor belts movable synchronously in the same direction for carrying between them the box shaped articles to be stamped, means for driving said belts, means

for guiding opposite substantially parallel portions of the belts first vertically upwardly and then in a curved path to a substantially horizontal plane, whereby the box shaped articles will be carried first in upright condition and then in a substantially flat condition along said horizontal plane, printing rollers arranged opposite the edges of the belts for printing upon opposite sides of the

box shaped articles as the belts move the same upwardly, a chute for receiving the articles moving along said horizontal plane, and guiding means for said articles detachably connected to said chute for guiding said articles away from 5 said chute.

JOSEF RÓNA.
